UNITED STATES PATENT OFFICE

GEORGE P. KINGSBURY, OF HOLLIS, NEW YORK, ASSIGNOR TO MERGENTHALER LINOTYPE COMPANY, A CORPORATION OF NEW YORK

TYPOGRAPHICAL DISTRIBUTING MACHINE

Application filed November 23, 1929. Serial No. 409,220.

This invention relates to typographical machines, such as linotype machines of the general organization represented in U. S. Letters Patent to O. Mergenthaler, No. 436,532, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter returned through distributing mechanism to the magazine from which they started.

Many modern machines of this type are equipped with a series of main magazines, which are adapted to contain the ordinary text fonts, and with one or more supplemental or auxiliary magazines arranged alongside the main magazines, and which are adapted to contain the larger head letter or display fonts, the distributing mechanism in such cases being extended to the right so that the matrices may be distributed thereby into both the main and auxiliary magazines. In these machines, the number of distributing combinations available (being based on the seven-rib system) is limited to one hundred twenty-four, ninety of which are utilized in the distribution of the matrices comprising the ordinary text fonts and the remaining thirty-four of which are utilized in the distribution of the matrices of the head letter or display fonts. The capacity of the auxiliary magazines is, therefore, greatly restricted, the fonts therein contained being limited to the upper case characters and numerals.

The present invention is intended to overcome these restrictions and contemplates means whereby the number of distributing combinations may be greatly increased or doubled if desired, so that full or complete sets of display matrices may be carried in the auxiliary magazines as well as full or complete sets of ordinary text fonts in the main magazines, and this without involving any departure from the regular seven-rib system or any change in the standard combinations of the matrices or distributor bar. To this

end, the distributor bar is formed with two duplicate series of matrix releasing combinations, one for the main magazines and the other for the auxiliary magazines, and means are provided to permit or prevent matrices delivered to the bar from being released by the first series of combinations according to whether a main or an auxiliary magazine is in use at the time. In the preferred embodiment illustrated, said means consist of a pair of rails extending along the opposite sides of the distributor bar throughout the first or main series of combinations and movable conjointly into and out of engaging relation to the upper projecting ears of matrices supported by the bar. When the rails are out of operative position, the matrices will be dropped from the first series of combinations into a main magazine, whereas when the rails are in operative position, the matrices will be carried across the bar and dropped from the second series of combinations into an auxiliary magazine.

In the accompanying drawings, the invention is shown merely in preferred form and by way of example and as applied to the particular kind of machine mentioned, but obviously many changes and variations may be made therein and in its mode of application which will still be comprised within its spirit. It should, therefore, be understood that the invention is not limited to any specific form or embodiment, except insofar as such limitations are specified in the claims.

Referring to the drawings:

Fig. 1 is a front elevation of the upper portion of a linotype machine embodying the present improvements;

Fig. 2 is an enlarged section through the distributing mechanism showing the means for adjusting the matrix sustaining rails;

Fig. 3 is a top plan view of the parts shown in Fig. 1 with the distributor supporting frame removed; and

Fig. 4 is a front elevation, partly in section, of the parts shown in Fig. 2, and illustrating the two series of corresponding matrix releasing combinations of the distributor bar.

In Fig. 1, the machine is shown as equipped

with a series of superposed main magazines A, and a second series of auxiliary magazines A¹, the two series being arranged side by side or in tandem. The main magazines A are provided with ninety-one grooves or channels to adapt them to contain matrices X of the regular ninety-character text fonts, while the auxiliary magazines A¹ are provided with seventy-two or fifty-five grooves or channels to adapt them to contain matrices X¹ of the regular head letter or display fonts. As will later appear, the auxiliary magazines could be provided with as many different matrix channels as the main magazines, whether the number be ninety as usual or one hundred twenty-four.

In the present embodiment, the matrices X, as they are released from the main magazines A, pass onto the constantly driven inclined belt B, which delivers them directly to the assembler C wherein they are composed in line under the influence of a star wheel C¹ against an upstanding line resistant finger C²; whereas the matrixes X¹, as they are released from the auxiliary magazines A¹, pass onto a separate inclined belt B¹ from which they are delivered to the assembler C by means of an intermediate horizontal belt B². This novel arrangement of the conveyor belts is intended to permit the assembling of the head letter or display matrixes at a maximum speed without danger of transposition, the matrixes in the course of composition being first directed by the inclined belt B¹ onto the receiving end of the horizontal belt B² one after another in the order of their release, and then delivered by the latter belt in the same order to the assembler C. After composition, the line is transferred to the mold (not shown) for casting and thereafter lifted to the distributing mechanism, which sorts them according to character and drops them into the magazine entrances A² for return to their appropriate magazine channels, all as is well understood in the art.

The distributor proper (see Fig. 2) comprises the usual ribbed or permuted distributor bar D, which supports the matrixes by their combination webs x, and the associated set of conveying screws D¹, which advances the matrixes by their projecting ears x¹ along the bar. The distributor bar D (best shown in Fig. 4) is formed with two successive groups or series of distributing combinations d¹, d², the first or main series d¹ at the left being adapted to release the matrixes X of the regular fonts into the main magazines A and hence corresponding in number of combinations to the different matrix channels formed in each of said main magazines, and the second or auxiliary series d² at the right being adapted to release the matrixes X¹ of the display fonts into the auxiliary magazines A¹ and hence corresponding in number of combinations to the different matrix chan-

nels formed in each of said auxiliary magazines.

Since the total number of different releasing combinations required for the two kinds of fonts herein employed (162 in one case and 145 in the other) greatly exceeds the number provided by the standard distributor bar (124), it is proposed, according to the present invention, to duplicate the matrix releasing combinations in the two series d¹, d² to whatever extent may be required, and to provide means for carrying the auxiliary matrixes X¹ entirely across the first series d¹ and render them subject to distribution solely by the second series d². The means employed for this purpose, as best shown in Fig. 2, consists of a pair of rails E formed on semi-tubular rods E¹ which partially envelop the two upper distributor screws D¹. These rods E¹ (see Fig. 3) are pivotally mounted by end supporting members E² on the spindles d³ of the said distributor screws D¹ so that, by rocking the rods about their pivotal axes, the rails E may be moved into and out of engaging relation with the upper projecting ears x¹ of matrices passing along the bar. The rails E, in the present instance, are solid or continuous and are made sufficiently long to extend throughout the first series of releasing combinations d¹, terminating (see Figs. 1 and 4) somewhat beyond the last combination of the series d¹, but at a point slightly in advance of the first combination of the series d².

Consequently, when the rails E occupy their active position (Fig. 2), matrixes undergoing distribution will be sustained by the rails during their travel across that section of the distributor bar devoted to the first series of releasing combinations d¹ and will be caused to drop as usual according to their characters from the second series of releasing combinations d². On the other hand, when the rails E occupy their inactive position (as indicated by the dotted lines in Fig. 2) matrixes undergoing distribution will receive no support from the rails and will be released according to character solely from the first series of combinations d¹. As a result of this arrangement, it is merely necessary to give the tubular rods E¹ a partial turn in one direction to bring about the distribution of the display matrixes X¹ into the auxiliary magazine A¹, or to give them a similar turn in the opposite direction to bring about the distribution of the regular matrixes X into the main magazines A.

In providing for the adjustment of the rods E¹ and rails E, a toggle device is employed, which is arranged in a transverse cut or recess d⁴ formed in the upper edge of the distributor bar D about midway of its length. The toggle device (as clearly shown in Figs. 2 and 3) consists of a pair of horizontally disposed links F¹, F², connected at their in-

ner ends to a centrally pivoted rocker plate F^3 and at their outer ends to upright arms E^3, E^4 rising from the tubular rods E^1 . The rocker plate F^3 is mounted on a screw stud F^4 fastened into one of the side walls of the notch d^4 and is formed with a forwardly projecting actuating arm F^5 by which the toggles may be extended and collapsed. A pull spring F^6 , anchored to the distributor beam O and which is connected to a lug e protruding from the outer surface of the tubular rod E^1 at the rear, tends constantly to rock the plate F^3 through the arm E^4 and link F^2 in a clockwise direction to collapse the toggles.

The arrangement is such that, when the actuating arm F^5 is pulled downwardly against the tension of the spring F^6 to extend the toggles, the rods E^1 will be turned to bring the rails E into action (see the full line showing in Fig. 2) and, when the arm F^5 is raised to collapse the toggles, the rods will be turned in the opposite direction to move the rails out of action (see the dotted line showing in Fig. 2). In order to locate the rails E in their adjusted positions, the movement of the arm F^5 in both directions is limited by a pair of stop fingers d^5, d^6 , the finger d^5 being secured to the upper edge of the distributor bar and adapted to stop the arm F^5 in its raised position, and the finger d^6 being secured to the front face of the distributor bar and adapted to stop said arm in its lower position. In this connection, it may be stated that as the arm F^5 engages the stop finger d^6 , the rocker plate will have just passed "dead center," so that the toggles are thus locked in opposition to the spring F^6 in their extended condition and the rails E maintained in their active position as determined by the stop finger d^6 .

Any suitable means (manual or automatic) may be employed for operating the toggle device to effect the adjustments of the rails E , but the means herein shown comprises a long vertical link G (Fig. 1), which is connected at its upper end to the actuating arm F^5 and at its lower end to an arm G^1 extending rearwardly from a short horizontal rock shaft G^2 , the latter being mounted in a fixed bearing bracket G^3 and controlled by a key button or thumb piece G^4 located conveniently adjacent the keyboard H . The key button G^4 is carried by a centrally pivoted fore-and-aft lever G^5 , which is mounted and guided in the keyboard frame and connected by a short vertical link G^6 to a crank arm G^7 extending forwardly from the rock shaft G^2 . By depressing the button G^4 , the rock shaft G^2 , through the lever G^5 and the connected crank arm G^7 , will be turned in one direction to pull the link G downwardly in extending the toggles, and by raising the key button G^4 , the rock shaft G^2 will be turned in the opposite direction to force the link G upwardly in collapsing the toggles.

It will now be seen that, when a display font is selected for use, the distributing mechanism may be instantly adapted to return the matrices into the active auxiliary magazine A^1 by depressing the key button G^4 . In other words, this operation, through the connections above described, extends the toggle links F^1, F^2 , and moves the rails E to and locks them in their active position, thereby shutting off the first or main series of bar combinations d^1 and bringing into use the second or auxiliary series of combinations d^2 . Matrices X^1 of the display fonts entering the distributor will thus be maintained by the rails E in engagement with the distributor bar D until they pass into engagement with that section thereof provided with the combinations d^2 , when they will be released according to character into the corresponding channels of the auxiliary magazine A^1 . Conversely, when the regular or text fonts are selected, the key button G^4 is raised to collapse the toggle links and cause the spring F^6 to move the rails E into and hold them in their inactive position, thereby rendering operative the first or main series of bar combinations d^1 to the exclusion of the second or auxiliary series of combinations d^2 . Matrices X of the regular or text fonts entering the distributor under such conditions will be released according to character from the combinations d^1 into the corresponding channels of the active main magazine A .

In the accompanying drawings, the invention, as previously stated, is shown only in preferred form by way of example, and as applied to a machine equipped with tandem magazines and provided with a distributor bar formed with two series of releasing combinations, but it will be obvious that the invention is equally applicable to a machine equipped with a single magazine and wherein the distributor bar is formed in a similar manner or with a lesser number of duplicate combinations, as for example a bar having only two like combinations. The extent of the adjustable rails in such instances would, of course, depend upon the relative location of the duplicate combinations on the bar. So far as the operation of the rails is concerned, this could be controlled automatically by the mechanical selection of the magazines or by the matrices themselves as they are moved onto or along the distributor bar. Moreover, while the distributor bar herein is shown as provided with but two groups or series of matrix releasing combinations, it could be provided with a greater number of groups or series simply by adding additional matrix sustaining rails. Thus, if the distributor bar had three groups of combinations, two sets of rails could be employed to control the selection of one or another of the groups. In this way, the number of distributing combinations (even though made

according to the standard seven-rib system) could be multiplied to any extent desired. Of course, the invention is not limited in its application to a seven-rib distributor bar, as it would be applicable to any form of bar having successive groups of duplicate combinations, but, as the commercial machines are equipped with seven-rib distributor bars to handle the standard seven-tooth matrices, the advantages of the invention become more pronounced by reference to the old system. These and other changes or modifications will readily occur to those skilled in the art and still be comprised within the scope of the invention.

Having thus described my invention, what I claim is:

1. A typographical distributing mechanism including, in combination, a distributor bar formed with a plurality of like matrix releasing combinations located at different points along the bar, and adjustable means associated with the distributor bar whereby matrices having corresponding combinations may be released in course of distribution by one or another of the said releasing combinations, as required.

2. A typographical distributing mechanism including, in combination, a distributor bar formed with successive groups or series of matrix releasing combinations, means for propelling the matrices along the bar, and means, adjustable into or out of action, for sustaining matrices while passing the combinations of the first group, so as to allow them to be distributed by the combinations of the second group.

3. A typographical distributing mechanism including, in combination, a distributor bar formed with successive groups of matrix releasing combinations, means for propelling the matrices along the bar, a pair of adjustable rails for sustaining matrices as they pass the first group of combinations, and means for adjusting the rails into or out of action, as required.

4. A typographical distributing mechanism including, in combination, a distributor bar formed with successive groups or series of matrix releasing combinations, means for propelling the matrices along the bar, a pair of matrix sustaining rails pivotally mounted and adapted conjointly to sustain the matrices by their projecting ears as they pass the first series of releasing combinations, and means for rocking the rails into or out of action, as required.

5. A typographical distributing mechanism including, in combination, a distributor bar formed with successive groups of matrix releasing combinations, the combinations of the first group being duplicated in whole or in part in the second group, means for propelling the matrices along the bar, a pair of adjustable rails associated with the first

group of combinations, and means for adjusting the rails conjointly into and out of action, the said rails being adapted in their active position to sustain the matrices so that they will reengage the distributor bar in advance of the second series of releasing combinations for distribution thereby.

6. In a typographical distributing machine adapted to be equipped with different sets of matrices, the combination of a distributor bar formed with successive groups or series of matrix releasing combinations, means for propelling the matrices along the bar, and means controlled by a finger key for selecting either of said series of combinations for use to the exclusion of the other, according to the particular set of matrices to be distributed.

7. In a typographical distributing machine adapted to be equipped with different sets of matrices, the combination of a distributor bar formed with successive groups or series of matrix releasing combinations, means for propelling the matrices along the bar, and matrix supporting means, adjustable at will into or out of action, associated with the first group of releasing combinations, said means being adapted in its active position to sustain the matrices of certain sets so that they will reengage the bar for release by the second group of bar combinations, and adapted in its inactive position to permit the release of matrices of other sets by the first group of bar combinations.

8. In a typographical machine adapted to be equipped with different sets of matrices, the combination of a distributor bar presenting in effect two distributing sections, one constituting a continuation of the other end each formed with a group or series of matrix releasing combinations, the combinations of the second section being duplicates in whole or in part of those of the first section, means for propelling the matrices along the bar, and means associated with the first section of the distributor bar for supporting the matrices of certain sets so that they will pass into engagement with the second section of the distributor bar, said means being adjustable into or out of action according to the particular set of matrices to be distributed.

9. In a typographical machine equipped with a main magazine and an auxiliary magazine arranged side by side or in tandem and containing different sets of matrices, the combination of a distributor bar formed with two successive groups or series of matrix releasing combinations, means for propelling the matrices along the bar, the first series of releasing combinations being located in operative relation to the channels of the main magazine, and the second series of releasing combinations being located in operative relation to the channels of the auxiliary magazine, and adjustable means associated with

the distributor bar and adapted in one position to carry the matrices from the auxiliary magazine across the first series of releasing combinations and deliver them for distribution to the second series of releasing combinations, and adapted in another position to permit the distribution of the matrices from the main magazine by the first series of releasing combinations.

10. A typographical distributing mechanism including, in combination, a distributor bar formed with two successive groups or series of matrix releasing combinations, two upper and one lower distributor screws for propelling the matrices along the bar, and a pair of matrix sustaining rails formed on tubular rods journaled on the trunnions of the upper distributor screws and extending along the opposite sides of that section of the bar formed with the first group of matrix releasing combinations, said rods being rotatable conjointly to swing the rails into and out of engaging relation to matrices supported by the distributor bar, for the purpose described.

11. A machine according to claim 9, equipped with an assembling mechanism for composing matrices from both magazines into a common assembler, such mechanism including a single conveyor belt to receive matrices from the main magazine and deliver them directly into the assembler, and two distinct conveyor belts to receive matrices from the auxiliary magazine and deliver them into the assembler.

12. A machine according to claim 9, equipped with an assembling mechanism for composing matrices from both magazines into a common assembler, such mechanism including an inclined conveyor belt to receive matrices from the main magazine and deliver them directly into the assembler, an inclined conveyor belt to receive matrices from the auxiliary magazine, and a second substantially horizontal conveyor belt to receive the matrices from the last-mentioned conveyor belt and deliver them into the assembler.

13. In a typographical machine, the combination of two matrix magazines arranged side by side or in tandem, an assembler wherein matrices of both magazines are composed in line, and independent conveyor belts arranged to receive matrices from the different magazines and separately deliver them into the assembler.

14. In a typographical machine, the combination of a main matrix magazine, an auxiliary matrix magazine arranged at the side thereof or in tandem thereto, an assembler wherein matrices from both magazines are composed in line, a conveyor belt to receive matrices from the main magazine and deliver them into the assembler, and an independent conveyor belt arrangement to receive

matrices from the auxiliary magazine and deliver them into the assembler without having to traverse the belt for the main magazine.

15. In a typographical machine, the combination of a main matrix magazine, an auxiliary matrix magazine arranged at the side thereof or in tandem thereto, an assembler wherein matrices from both magazines are composed in line, an inclined conveyor belt to receive matrices from the main magazine and deliver them directly into the assembler, a separate inclined belt to receive matrices from the auxiliary magazine, and a substantially horizontal belt arranged to receive the auxiliary matrices from the inclined belt and deliver them into the assembler independently of the conveyor belt for the main magazine.

In testimony whereof, this specification has been duly signed by:

GEORGE P. KINGSBURY.
